Related U.S. Application Data**CLAIM**

(63) Continuation-in-part of application No. 29/134,867, filed on Jan. 3, 2001, now Pat. No. Des. 463,394.

The ornamental design for a combined disc player and radio receiver, as shown.

DESCRIPTION

(51) **LOC (7) Cl.** **14-01**
(52) **U.S. Cl.** **D14/168; D14/156**
(58) **Field of Search** D14/135-136,
D14/156-157, 167-168, 188, 193-198,
257-258; 369/75.1, 75.2, 77.1, 77.2; 455/344,
347, 350-351

FIG. 1 is a perspective view of a combined disc player and radio receiver showing my new design;
FIG. 2 is a front elevational view thereof;
FIG. 3 is a left side elevational view thereof;
FIG. 4 is a right side elevational view thereof; and,
FIG. 5 is a bottom plan view thereof.
The broken line showing on FIGS. 1-5 is for illustrative purposes only and forms no part of the claimed design.
